CLAIM

The ornamental design for an electronic cigarette case, as shown and described.

DESCRIPTION

FIG. 1 is a side perspective view of the new design of an electronic cigarette case;

FIG. 2 is another side perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof;

FIG. 8 is a bottom view thereof; and,

FIG. 9 is a side perspective view thereof, illustrating that a cover of the electronic cigarette case is opened.

The broken (dashed) lines show portions of the electronic cigarette case that form no part of the claimed design.
